SMOOTHING MATERIAL.

1,192,219.

Specification of Letters Patent. Patented July 25, 1916.

Application filed May 25, 1915. Serial No. 30,414.

To all whom it may concern:

Be it known that we, JOHN R. MONTGOMERY and GEORGE M. MONTGOMERY, citizens of the United States, and residents of Windsor Locks, in the county of Hartford and State of Connecticut, have invented certain new and useful Improvements in Smoothing Material, of which the following is a specification.

10 This invention relates to an improved smoothing material which may be made in different degrees of fineness for the purpose of smoothing and finishing roughened surfaces, removing paint, varnish, etc., and 15 used in a way similar to that in which what is commonly known as sandpaper or emery cloth is used.

The object of the invention is to produce a material of this general nature which will 20 be very efficient and quite indestructible.

In the drawings—Figure 1 indicates generally a mass of the material as it is ready for use. Fig. 2 shows on enlarged scale a piece of composite strand. Fig. 3 shows on 25 enlarged scale a piece of compound strand. Fig. 4 shows on enlarged scale a piece of compound strand of a coarser grade than that shown in Fig. 3.

The material forming the subject matter 30 of this invention comprises a pliable core of cotton or other pliable fiber upon which is wound a very fine ribbon of metal, such for instance as steel or copper, this ribbon being flattened out to such a degree that its edges 35 are fairly sharp. This metallic ribbon is wound spirally onto the cotton core more or less tightly, as will be best adapted to the particular fineness of the material being made, and as the composite strand is completed a sufficient amount of it is thrown 40 loosely and allowed to kink and snarl naturally owing to the twist of the core, so that it produces a tangled snarled bunch of material of a size for instance which will fill 45 the palm of the hand. The pliable core supports the metallic ribbon and prevents its being bent so sharply as to cause it to break and splinter off, and the snarling produced by the natural untwisting action of the core 50 has a tendency to throw the edge of the me-

tallic ribbon out slightly causing it to become effective as a smoothing agency. When desired the mass can be shaken out and then compacted again, and it will be seen that it is always presenting new working surfaces of the metallic ribbon, giving to the material a long life and high efficiency.

For coarser work, a slightly heavier core and metallic ribbon may be used, and if desired two of the composite strands may be twisted together to form what I term a compound strand. The twisting together of the two composite strands, and then the normal untwisting tendency of the core, cause the metallic ribbon to stand out from the core, presenting very effective cutting and smoothing edges. If the mass of the material being used becomes filled with dust or dirt, it can all be readily shaken out, and the mass always maintained in a clean and efficient condition. It can be used with the bare hand without any danger of splinters being driven into the flesh, and since the material is very pliable, and in its kinked- 75 up or snarled condition provides an infinite number of working edges, it will readily follow uneven surfaces and produce a uniform and even finish on the work.

Where non-corroding metals, such as 80 copper, are used for the ribbon, the material becomes an effective household utensil, useful for cleaning paint, pans, dishes, etc., and may be washed and cleansed and so maintained in an extremely sanitary and 85 efficient condition.

It can be made in a variety of grades, from very coarse to very fine, to cover a wider range than can be covered by the usual sandpaper, steel wool or emery, and 90 prove at least equally efficient, and under ordinary conditions of use its life is almost limitless, particularly as compared with the life of the above mentioned articles.

We claim as our invention:

1. A material of the character described, comprising a pliable core and a metallic ribbon wound about said core.
2. A material of the character described, comprising a pliable core and a metallic 100

ribbon wound about said core, the resulting strand being formed into a loose tangled mass.

3. A material of the character described, comprising a pliable core and a flat metallic ribbon having a sharp edge wound spirally about said core.

4. A material of the character described, consisting of a tangled snarled mass formed

from a composite strand comprising a pliable core and a flexible flat metallic ribbon wound about said core.

JOHN R. MONTGOMERY.
GEORGE M. MONTGOMERY.
